UNITED STATES PATENT OFFICE.

ALBERT E. MAYNARD, OF SOUTHBIDGE, MASSACHUSETTS, ASSIGNOR TO AMERICAN OPTICAL COMPANY, OF SOUTHBIDGE, MASSACHUSETTS, A VOLUNTARY ASSOCIATION OF MASSACHUSETTS.

SURFACING MACHINE.

Application filed December 4, 1926. Serial No. 152,555.

This invention relates to surfacing machines and has particular reference to a lap form of surfacing machine in which a plurality of pieces of work are maintained against the lap under approximately equalized surfacing pressures during the surfacing operation.

The principal object of the invention is to provide improved means for approximately equalizing the surfacing pressure of a plurality of pieces of work against the lap for all positions of the work on the lap during the surfacing operation.

Another object of the invention is to provide improved means for holding the work against the surfacing lap so that it will be surfaced equally throughout the surfacing operation, that is to say, the work will not be thicker or thinner on one side but the surfacing will be maintained equally from the first contact until the finished surface has been made.

Another object of the invention is to provide improved means for regulating the surfacing pressure on the work during the surfacing operation.

Another object of the invention is to provide improved means for regulating the path the work will take on the lap during the surfacing operation.

Another object of the invention is to provide simple, economical and efficient means for substantially equalizing and regulating the surfacing pressure on a plurality of pieces of work during the surfacing operations.

Other objects and advantages of the invention will become apparent from the following description taken in connection with the accompanying drawings and many changes may be made in the details of construction and arrangement of parts without departing from the spirit of the invention as set forth in the accompanying claims. I, therefore, do not wish to be limited to the exact details of construction and arrangement shown, the preferred forms of the invention only having been shown by way of illustration.

Referring to the accompanying drawings: Figure 1 is a partial elevation of a sur-

facing machine to which the invention is applied;

Figure 2 is a top or plan view of Figure 1 with parts removed for clearness;

Figure 3 is a cross section on line 3—3 of Figure 1;

Figure 4 is a partial elevation similar to Figure 1 showing the invention applied to a concave lap instead of to a convex lap.

Prior to my invention it has been customary to hold the work against the surfacing lap by means of spring pressure applied on the central spindle of the machine. It will be seen, therefore, that when the work is at the bottom portion of the lap the spring pressure is much weaker than when it is at the top portion of the lap and that the spring pressure varies greatly in between these two portions of the lap. Therefore, there is a tendency for the work to be ground unequally, grinding faster at one place than at another, which tendency has been found from practice and from experience to very often cause the work to be ground thinner on one side than on the other.

It is, therefore, the prime object of this invention to substantially overcome these disadvantages of the prior art and to provide pressure equalizing means that will insure that a plurality of pieces of work have approximately the same surfacing pressure whether grinding at the bottom or the top or at points in between on the lap, and also due to this reduction in unequalized pressure the work will have a tendency to be surfaced equally so that the finished product will be of uniform thickness instead of being thinner on one side than the other. This is of particular importance in the surfacing of ophthalmic lenses which are ground from fragile optical glass which is an expensive material and in which the wastage has been large in the prior art surfacing machines due to the tendency of the glass material to become broken when shifting from the lower to the higher side of the lap, particularly where the spring pressure was not properly adjusted.

sponding parts throughout, the work or ophthalmic lens 1 is secured to a work holder 2 by means of an adhesive such as pitch or cement 3. The holder 2 has a conical centering point 4 into which is fitted the conical point 5 of the positioning pin 6. The positioning pin 6 is carried on an equalizer member 7 which is pivoted at 8 to the shank 9 which is secured to the spindle 10 of the surfacing machine by means of the stud 11 held in place by the set screw 12. The positioning pin 6 has a shoulder 13, see Fig. 3, on which rests the spiral spring 14. The positioning pin 6 is carried in the bore of a clamp member 15 into which is screw threaded the regulator cap 34 for regulating the spring pressure by screwing down the cap on the spring 14. The clamp member 15 fits into clamps 16 and 17 which secure it to the equalizer member 7, the clamp 17 being screw threaded on to the end of the clamp member 15 and the clamp portion 16 having the annular bore fitting over the member 15. The equalizer member 7 is engaged between the jaw 18 of the member 16 and the jaw 19 of the member 17 and held in place thereon by the lock nut 20 which is threaded on the clamp member 15, the equalizer member 7 having a dove-tail 21 to prevent separation of the parts.

The pivot 8 is eccentric or off to one side of the center line of the spindle 10 of the surfacing machine. The spindle 10 is driven by the pulley 22 and the belt 23 and the spindle 10 is raised from the lap 24 or depressed towards it by means of the lever 25 having the handle 26, the lever 25 being pivoted at 27 to the frame 28 of the surfacing machine. The lap 24 is driven by the spindle 29 by means of the pulley 30 and the belt 31.

The equalizer member 7 is pivoted at 8 to the shank 9, which has a stud 11 entering the spindle 10. The stud 11 is related to the shank 9 in such a way that if the set screw 12 is loosened and the shank 9 turned about the stud 11 the center of the pivot 8 may be positioned at points varying from the center line of the spindle 10 to the point shown in Fig. 1, that is to say, it may be positioned at any point between the position on the center line of the spindle 10 and the extreme distance therefrom by rotation of the shank member 9 on the stud 11 in its fitting in the spindle 10.

The positioning pin 6 in the clamp member 15 is positioned on the dove-tail 21 of the equalizer member 7 by means of the clamp members 16 and 17 and the lock nut 20 in such a way that the pin 6 may be angled as desired to a point normal to the work on the lap in desired position. After it has thus been positioned the clamps 16 and 17 are tightened by means of the lock nut 20 to hold the pins in the desired related posi-

tion to the work. It will, of course, be understood that the angles at which these pins 6 are approximately pointed towards the lap would be radial to the center of curvature of the lap, that is, the center of curvature to which the lap is to be surfaced. On the equalizer member 7 adjacent the points where the positioning pins 6 are located is a scale 32 and a registering mark 33 on the clamp jaw 18 by which the amount of inclination of the spindle may be determined. The center of the spindle 10 is also eccentric to the center of the spindle 29 of the lap as shown in Fig. 1.

The operation of the invention is as follows: A lap 24 of desired curvature, either convex as shown in Fig. 1, or concave as shown in Fig. 4, is placed on the spindle 29. The work secured to the holder 2 is placed on the lap, the pin 6 is entered into the recess 4 of the holder 2, and the pin 6 set to the required angle with respect to the lap, that is to say, radially to the center of the lap, and locked in position by means of the lock nut 20. The equalizer 7 being pivoted on the pivot 8 is free to adjust itself so that the pins 6 bearing on the work pieces hold each of the work pieces in its true respective position on the lap, the spring surfacing pressure being exerted along the pins 6 by means of the spiral spring 14 in the clamp member 15, the spring pressure having been adjusted by the adjusting screw 34. The machine is then set in operation, the lap being rotated and the spindle 10 rotated. The spindle 10 being eccentric to the spindle 29 and the pivot point 8 of the equalizer 7 being eccentric to the center line of the spindle 10 will cause the work to move up and down on the lap, that is, from the lower point towards the center and vice versa as the equalizer 7 is being rotated by the spindle 10. The positioning pins 6 being carried by the equalizer 7 and moving therewith will always exert the same pressure on the work 1 regardless of whether the work is at the bottom of the lap, at the top of the lap or at positions in between. As has been stated, the amount of eccentricity of the pivot 8 is regulated by the shank 9 moving on its stud 11 on the spindle 10, this being capable of being set either on the center of the spindle 10 or at positions therefrom up to the maximum amount. The spring pressure exerted on the work through the pins 6 being equal in all positions of the work on the lap insures that the surfacing operation is carried on at an equal rate of surfacing and that the tendency of the work is to be surfaced equally or centrally rather than having a tendency to grind on the lower side, it having been found in the prior art machines that there was a tendency for the lens to grind thick on the lower side and to stop turning as it was brought towards the center.

of the lap. The arrangement of this invention is such as to practically eliminate these disadvantages. The positioning pins 6 are advanced towards the work, are retracted therefrom at the termination of the surfacing operations by means of the lever 25 and handle 26, the lever 25 having locking arrangements for securing the spindle 10 in the proper adjusted position for grinding.

19. While I have shown my invention as applied to one particular form of surfacing machine it may be applied to many different kinds of surfacing machines, and while I have shown my device as applied to the surfacing of ophthalmic lenses other forms of lenses and other forms of surfacing may be equally well done with this apparatus.

It will be seen that the pressure exerted by the springs 14 on the pins 6 is equalized 20 by the equalizer member 7 operating about the pivot 8 because as one piece of the work is on a low portion of the lap another piece of the work is on the higher portion of the lap and as these two pieces change their 25 positions on the lap the equalizer 7 rocks on the pivot point 8. Therefore, they act as a couple and the pressure exerted by the spring 14 on the pins 6 is equal in all positions of the work on the lap. It is clear that the two 30 pins 6 are so located with respect to the lap that in the movement of the work over the lap there is an effect to neutralize each other, that is, as one spring is tightened the other is loosened by an equal amount so the pressure 35 exerted by the couple is always equalled.

From the foregoing description it will be seen that I have provided simple, efficient and economical means for carrying out all the objects of the invention, particularly 40 equalizing the pressure on the work during the operation and overcoming the difficulties encountered in prior art machines, especially the unequal surfacing and unequal speed of surfacing as well as insuring a uniform and 45 constant wear on the surfaces of the laps themselves.

Having described my invention, I claim:

1. In a surfacing machine in combination with a tool and spindle, an equalizer member 50 movably connected with the spindle having a pair of arcuate portions thereon, yielding positioning pins slidably carried by the arcuate portions and means to lock the positioning pins on the arcuate portions at the desired angle with respect to the tool.

2. In a surfacing machine in combination with a tool and a spindle, a member movably secured to the spindle so that it may be

55 moved to center with the center line of the spindle or be eccentric therewith, an equalizing member movably connected with the first member and having a pair of arcuate portions thereon, a plurality of positioning pins 60 slidably carried by the arcuate portions, and means for securing the positioning pins on 65 the arcuate portions at the desired angular relation with respect to the tool.

3. In a surfacing machine in combination with a tool and spindle, an equalizer member 70 movably connected with the spindle having a pair of arcuate portions with slide means thereon, members having internal recesses adapted to slide on the arcuate portions, reciprocal pins in the recessed member, yielding means in the recessed members adapted 75 to yieldingly urge the reciprocal pins outwardly from the recessed members against work holders which are adapted to present the work to the tool, and means to lock the recessed members on the arcuate portions 80 of the equalizer member to position the positioning pins at the desired angle with respect to the tool.

4. In a surfacing machine in combination with a tool and spindle, an equalizer member 85 movably connected with the spindle having a pair of arcuate portions with slide means thereon, members having internal recesses adapted to slide on the arcuate portions, reciprocal pins in the recessed members, yielding means in the recessed members adapted 90 to yieldingly urge the reciprocal pins outwardly from the recessed members against work holders which are adapted to present the work to the tool, means to lock the recessed members on the arcuate portions of the equalizer member to position the positioning pins at the desired angle with respect to the tool, and means to regulate the yielding pressure 95 of the yielding means in the recessed members. 100

5. In a surfacing machine in combination with a tool and spindle, a supporting member movably connected in eccentric relation to the end of the spindle, an equalizer member 105 movably connected with the supporting member and having a pair of arcuate portions thereon, said arcuate portions having slide means, yielding positioning means slidably carried by the arcuate portions of 110 the equalizer member and adapted to engage the work holding means for urging the same toward the tool, and means to lock the positioning pins on the arcuate portions at the desired angle with respect to the tool.

ALBERT E. MAYNARD.
